Attorneys.

UNITED STATES PATENT OFFICE

2,314,223

PIN

Madge Sanford Lane, Chicago, Ill.

Application April 11, 1940, Serial No. 329,079

1 Claim. (Cl. 24—155)

This invention relates to pins for a wide variety of ornamental and utilitarian purposes, and it has for its object the provision of a pin having a new and improved form and arrangement of parts by reason of which the production of the parts and their assembly into unit form shall be accomplished readily and easily at a minimum of trouble and expense, and the pin shall be capable of being quickly and easily applied so as to retain its position without danger of being loosened accidentally while at the same time the pin can be removed readily when desired.

For attaining these objects, two end members which are ordinarily in the form of ornaments are employed, one of said end members being provided with a shaft or pin which has a working fit in the opening of a socket part carried by the other end member, said end members being connected together by means of an elastic, preferably in the form of a cord, comprising a slender strip or thread of rubber covered by a silk braid. The cord is preferably connected with the end members by being knotted at both ends, with each of the knots engaging a notched or otherwise apertured part through which the cord extends. A plurality of forms of apertured part for holding the cord by engagement with the knots are shown by the drawing, each of such forms being arranged for ready production and convenient use for assembly purposes.

It is another object of this invention to improve devices of this type in sundry details hereinafter pointed out. The preferred means by which the several objects have been attained are illustrated in the accompanying drawing, in which—

Fig. 1 is a face view of my improved pin with the parts in holding engagement;

Fig. 2 is a view similar to Fig. 1 but with one of the end members in increased spaced relation to the other end member;

Fig. 3 is a central vertical sectional view on an enlarged scale through the end member at the left in Fig. 1, some of the parts being broken away for clearness of illustration;

Fig. 4 is a vertical sectional view taken substantially at the line 4—4 of Fig. 3;

Fig. 5 is a central vertical section on an enlarged scale through the end member at the right in Fig. 2;

Fig. 6 is a view similar to Fig. 4, but showing on a somewhat reduced scale a modified form of structure;

Fig. 7 is a face view of a modified form of pin with the parts in holding engagement;

Fig. 8 is a rear face view of the structure shown in Fig. 7; and

Fig. 9 is a face view of a fragmentary portion of the end member at the left in Fig. 8 prior to the assembly of the mounting and holding means therewith.

Referring now to Figs. 1 to 5, inclusive, in which corresponding parts are indicated by the same reference characters, 15 and 16 indicate 10 the end members of a pin device, such end members in the arrangement shown being in the form of ornamental heads formed of wood or other suitable material and decorated so as to be attractive. Each of the heads 15 and 16 is provided with a tubular mounting member 17 fixedly secured therein, each of said tubular mounting members being provided with a facing plate 18 on its outer end in position to cover a portion of the end member. In the arrangement as 15 shown in Figs. 3 and 5, the facing plates 18 are positioned in spaced relation to the end members at their middle portions so as to provide open spaces about the outer ends of the tubular mounting members 17.

25 As is best shown in Fig. 3, the tubular member 17 of the end member 15 is provided with a shaft or pin 19 fixedly mounted therein so as to be held immovable with respect to said end member. As is clearly indicated in Fig. 5, the shaft 19 is of a size to have an easy working fit in the opening 20 through the tubular mounting member 17 of the end member 16.

30 In the arrangement shown (see Fig. 4) the facing plate 18 is in the form of a rosette so as to provide a series of notches 20 in the plate for the reception of an elastic tie member as hereinafter described. The plate 18 in connection with the end member 16 is similarly formed and arranged.

Between the facing plates 18 of the end members 15 and 16, I have provided an elastic tie member 21 in the form of a cord, such cord being knotted at both ends with the knots 22 engaging the inner faces of the facing plates 18, such cord being mounted in oppositely disposed notches 20 in said two facing plates. The length of the cord 21 between the knots 22 is such that when the shaft 19 is in engagement with the mounting member 17 of the end member 16 in the arrangement as shown in Fig. 1, the cord serves to hold the parts yieldingly in their engaged position. When a slight pressure is applied upon the end members in the direction directly longitudinally of the shaft, the end members are moved outwardly against the action of the resilient cord

so as to disengage the shaft 19 from the head 16, as is shown in Fig. 2.

The arrangement is such that my improved pin can be very quickly and very easily applied in position at any point where it is desired for ornamental or utilitarian purposes. I have found that the pin is very useful for holding a corsage of fresh or artificial flowers, with the corsage held in position by the elastic rather than by the shaft. As will be readily understood, the pin might be used for ornamental purposes in any of a great number of applications in connection with wearing apparel of many kinds. The pins could be used to advantage as drapery tie-back devices. The pins could also be used to advantage at any point where closure devices are required,—in connection with gloves, for example.

In Fig. 6, I have shown a modified form of arrangement in which an end member 23 is shown in the form of a shell filled with paraffin or other suitable material as indicated at 24. A modified form of facing plate 25 also is shown held in position by means of a mounting member 26, the plate 25 being provided with a single opening therethrough for the passage of the end of the elastic cord 27 in lieu of the notched arrangement as shown in Fig. 4. The cord 27 is knotted at its end at 28 for limiting the movement of the cord with respect to the plate 25.

In Figs. 7, 8 and 9, still another form of pin is shown comprising end pieces 29 and 30 in the form of sheet metal stampings. In the arrangement as shown in Fig. 8, a shaft 31 is secured upon the end member 30 by means of soldering as shown at 32. For receiving the shaft 31, a tubular socket member 33 is provided upon the end member 29, such socket member being also secured in position preferably by being soldered

directly to the end member. An elastic tie member 34 knotted at 35 at each end is connected with the end members 29 and 30 by means of lugs 36 formed with the end members so as to be capable of being bent into the form of hooks having holding engagement with the tie member as shown in Fig. 8.

By the use of my improved arrangement comprising the tie member in the form of an elastic cord knotted at its ends for limiting the movement of the cord with respect to the notched or apertured parts to which the cord is connected, I have provided an arrangement which is very effective and which can be very quickly and easily assembled so as to reduce to a minimum the trouble and expense of manufacture and assembly of the device. The arrangement is such that the pin is not likely to become loosened accidentally, while at the same time it can be very quickly and easily removed when desired.

It is to be understood that my invention is not limited to the form of parts as shown, except so far as the claim may be so limited, since changes might well be made in the arrangement without departing from my invention.

I claim:

In a device of the type described, the combination of two end members stamped out of sheet metal, a shaft secured to one of said end members and adapted to releasably engage a socket portion of the other end member, lugs formed integrally on said end members so as to be bent into the form of hooks, and a resilient connecting member engaging said hooks serving normally when said shaft is in engagement with said socket piece to hold the shaft yieldingly from disengagement.

MADGE SANFORD LANE.
